UNITED STATES PATENT OFFICE

157,620

FINGER RING

Benjamin Novgrad, Newington, Conn., assignor
to Arts and Crafts Company, Hartford, Conn.,
a partnership

Application December 21, 1948, Serial No. 150,308

Term of patent 7 years

(Cl. D45—10)

To all whom it may concern:

Be it known that I, Benjamin Novgrad, a citizen of the United States, residing in Newington, in the county of Hartford, State of Connecticut, have invented a new, original, and ornamental Design for Finger Rings, of which the following is a specification, reference being had to the accompanying drawing, forming part thereof.

In the drawing,

Fig. 1 is a plan view of the ring showing my new design with the seal uppermost.

Fig. 2 is a view of the ring taken from a point at the right of the seal, Figs. 1 and 4, in a direction toward the central portion of the finger opening in the ring, at an angle of about 30° to the plane of the margin of the seal, with the design inside the margin of the seal omitted to simplify the drawing.

Fig. 3 is a view in elevation of the ring, taken from a point at the left of the seal, Figs. 1 and 4, in a direction toward the central portion of the finger opening at an angle of about 30° to the

plane of the margin of the seal, also with the design inside the margin of the seal omitted.

Fig. 4 is a view in side elevation of the ring.

I claim:

The ornamental design for a finger ring, as shown and described.

BENJAMIN NOVGRAD.
